W. RAYMOND

COMPRESSOR REGULATOR

Filed Sept. 3, 1925

UNITED STATES PATENT OFFICE.

WARD RAYMOND, OF EASTON, PENNSYLVANIA, ASSIGNOR TO PENNSYLVANIA PUMP & COMPRESSOR COMPANY, OF EASTON, PENNSYLVANIA, A CORPORATION OF PENNSYLVANIA.

COMPRESSOR REGULATOR.

Original application filed January 29, 1925, Serial No. 5,544. Patent No. 1,575,002, dated March 2, 1926.
Divided and this application filed September 3, 1925. Serial No. 54,274.

This invention relates to compressors and more particularly to regulators therefore adapted to maintain the compressor unloaded until it has acquired substantially normal speed, and also adapted to unload the compressor when a predetermined pressure is reached.

An object of the present invention is to provide an intake closing valve opened and closed through a centrifugal member, and also to provide cylinder relief valves simultaneously operated by the same centrifugal member to unload the compressor.

A further object is to provide a pilot valve actuated by a centrifugal member which, when opened by action of the centrifugal member, admits fluid under pressure simultaneously to the relief valves and to the inlet closing valve to maintain the compressor completely unloaded.

Another object of the invention is to provide simultaneous acting means to open cylinder relief valves for a compressor cylinder and to close an inlet valve so that a compressor can be quickly and completely unloaded.

With the above and other objects in view, my invention consists in the features of construction and operation set forth in the following specification and illustrated in the accompanying drawing.

In the accompanying drawing annexed hereto and forming a part of the specification, I have shown my invention embodied in a single cylinder double acting air compressor of medium size and adapted for a belt drive, but it will be understood that the invention can be otherwise embodied and that the drawing is not to be construed as defining or limiting the scope of the invention, the claims appended to this specification being relied upon for that purpose.

In the drawing:

Figure 1 is a side elevation of a compressor provided with the present form of unloader, parts being broken away to more clearly disclose their construction,

Fig. 2 is a plan view of the centrifugal element and pilot valve forming a part of this invention, and,

Fig. 3 is a cross sectional view of the inlet closing valve.

In the above mentioned drawing I have

shown but one embodiment of the invention which is now deemed preferable, but it is to be understood that changes and modifications may be made within the scope of the appended claims without departing from the spirit of the invention.

My invention, briefly and in its broadest aspect, comprises the following principal parts: first, an intake closing valve; second, fluid actuated means for closing said valve; third, cylinder relief valves; fourth, a centrifugal element rotating during operation of the compressor; fifth, a pilot valve; and sixth, conduits connecting the pilot valve with said inlet closing and relief valves.

Referring more in detail to the figures of the drawing, I show a compressor cylinder 10, which, in the embodiment selected for illustration, is of the double acting type. The discharge outlet is shown at 11 and the intake passage at 12 within which passage is a valve 13. This intake valve 13 may be of the type shown in my Patent No. 1,510,161 granted September 30, 1924. Preferably, however, this valve 13 is of the construction shown and claimed in Patent 1,575,002 granted March 2, 1926, of which the present application is a division. Two separate fluid actuated means are provided for closing the valve 13 to unload the compressor. As these means form no part of the present invention, further detail description is not thought to be necessary. A spring 14 within the body portion 15 of this inlet valve normally holds the valve 13 in its open position.

Relief valves 16, one of which is shown in section, are provided adjacent each end of the cylinder 10. These valves, when in their open position, permit the fluid within the cylinder 10 to be exhausted through them without compression. These valves 16 are also adapted to be moved to their open or unloading position by fluid actuated means. For this purpose the relief valves 16 are provided with pistons 17 in their lower portions and moved by fluid supplied through conduits 18.

As shown in Figs. 1 and 2, the main shaft 20 of the compressor is provided with a centrifugal element 21. This member 21 is forced normally to a position nearer the axis

of rotation of shaft 20 by a spring 21 and, during operation, the rotative motion of this shaft 20 moves the member 21 away from this position due to its centrifugal force. 5 This movement of the centrifugal element 21 is made to open and close a pilot valve 22. As this pilot valve 22 controlling mechanism is or may be similar in every way to that disclosed in my Patent No. 1,561,886, 10 granted November 17, 1925, further description will be unnecessary. It will be sufficient to state that during the starting of the compressor, the pilot valve 22 will be open to supply discharge pressure from the receiver 15 by means of a conduit 23 to the conduit 24 leading to the unloaders or relief valves 16. The effect of this will be to open the relief valves 16 and thus maintain the compressor unloaded until substantially normal operating speed is reached. At this normal speed 20 of operation the pilot valve 22 closes, permitting the relief valves 16 to close and the compressor continues its normal operation.

Simultaneously with the opening of the 25 relief valves 16 by fluid pressure supplied through conduit 24, the inlet valve 13 is also closed. By means of a branch conduit 25, fluid under pressure is admitted to a point 26 within the head portion 27 of this valve 13. 30 This forces the piston 28 against the valve member 13 and moves it to its closed position against the valve seat 30. The compressor will therefore be completely unloaded so long as pressure exists in the conduit 24. 35 Preferably, and as shown in Fig. 1, a small receiver 31 is inserted in the conduit 24 to increase the amount of fluid in this conduit. As the pilot valve 22 is provided with a small leak port 33, the small receiver 31 40 maintains pressure within the conduit 24 for only a short interval of time after the pilot valve 22 is opened. This permits the compressor to acquire full normal speed before the working load is finally put on the 45 compressor.

The inlet valve 13 in addition to the actuating means described above may be provided with a conduit 34 extending from the compressor discharge pipe so that the inlet 50 valve 13 will be closed automatically when the receiver pressure is above a predetermined limit. As this operation of the valve 13 is similar in every way to the operation described in the above mentioned Patent 55 1,575,002, it is not thought that further description will be necessary. The conduit 34 enters the valve casing 13 above a diaphragm 40.

In operation, as the compressor starts 60 from rest with pressure within its receiver, the relief valves 16 exhaust the fluid within the cylinder 10 and, as the speed is slow, but small relief valves 16 are required. Before the compressor has acquired appreciable 65 speed, the inlet valve 13 has closed to pre-

vent further admission of fluid so that the pressure in the intake is reduced below atmosphere. As soon as substantially normal speed has been acquired, the fluid within the conduits 24, 18 and 25 is permitted to leak 70 out through port 33, thus permitting the relief valves 16 to close and the inlet valve 13 to open. Within an extension formed on the inlet valve casing 13 is a spring 37, the pressure of which determines that at which fluid within conduit 34 will close the inlet valve 13. By means of a screw 38 the pressure exerted by spring 37 may be widely varied. One end of the spring 37 bears 75 against diaphragm 40 movement of which admits fluid from conduit 34 to the space above the piston 28.

In addition to actuating the unloading devices, fluid pressure within conduit 24 may be admitted by conduit 18 to control a valve 80 85 35 in the water circulating pipe 36. By this valve 35 the circulation of cooling water is discontinued when the compressor is unloaded.

What I claim is:

1. A regulator for a compressor comprising in combination, a centrifugal element adapted to be rotated during operation of the compressor, an inlet closing valve, a cylinder relief valve, means controlled by movement of said element to simultaneously close said inlet closing valve and open said relief valve, means to operate the inlet closing valve independently of said relief valve, and means to permit simultaneous opening of said inlet closing valve and closing of said cylinder relief valves. 90 95 100

2. A regulator for a compressor comprising in combination, a centrifugal element adapted to be rotated during operation of the compressor, an inlet closing valve, a cylinder relief valve, fluid pressure means controlled by movement of said element to simultaneously close said inlet closing valve and open said relief valve, means to operate the inlet closing valve independently of said relief valve, and means to permit simultaneous opening of said inlet closing valve and closing of said cylinder relief valves. 105 110 115

3. A regulator for a compressor comprising in combination, a centrifugal element adapted to be rotated during operation of the compressor, a pilot valve opened and closed by movement of said centrifugal element, a cylinder relief valve, an inlet closing valve, fluid pressure conduits extending from said pilot valve to said relief and intake closing valves whereby said valves may be operated by said fluid pressure means, and independent means for closing said inlet closing valve. 120 125 130

4. A regulator for a compressor comprising in combination, a centrifugal element adapted to be rotated during operation of the compressor, a pilot valve opened and 135

ctosed by movement of said centrifugal element, a cylinder relief valve, an inlet closing valve, fluid pressure conduits extending from said pilot valve to said relief and inlet closing 5 valves whereby said valves may be operated by said fluid pressure means, and independent fluid pressure operated means for closing said inlet closing valve when the pressure of fluid compressed exceeds a pre- 10 determined amount.

5. A regulator for a compressor comprising in combination, a centrifugal element adapted to be rotated during operation of the compressor, a pilot valve opened and closed 15 by movement of said centrifugal element,

a cylinder relief valve, an inlet closing valve, fluid pressure conduits extending from said pilot valve to said relief and inlet closing valves whereby said valves may be operated by said fluid pressure means, independent 20 fluid pressure operated means for closing said inlet closing valve when the pressure of fluid compressed exceeds a predetermined amount, and means permitting adjustment of the pressures at which said inlet closing 25 valve may operate by said controlling means.

In testimony whereof, I hereto affix my signature.

WARD RAYMOND.
